UNITED STATES PATENT OFFICE.

HENRY S. KELLEY, OF CAIRO, WEST VIRGINIA.

ICE-CREEPER.

SPECIFICATION forming part of Letters Patent No. 740,021, dated September 29, 1903.

Application filed May 15, 1903. Serial No. 157,294. (No model.)

To all whom it may concern:

Be it known that I, HENRY S. KELLEY, a citizen of the United States, residing at Cairo, in the county of Ritchie and State of West Virginia, have invented certain new and useful Improvements in Ice-Creepers, of which the following is a specification.

My invention relates to antislapping devices for boots and shoes; and it consists of a frame shaped to fit the outline of the heel and so constructed as to be expansible when being applied to or removed from the heel and contracted to hold it in position on the heel.

The construction, operation, and advantages of my invention are fully explained hereinafter and by referring to the accompanying drawings, in which—

Figure 1 is a top plan view of my invention, showing the parts closed; Fig. 2, a bottom view showing the parts open to be applied to or removed from the heel; Fig. 3, a cross-section of one of the parts of the device, and Fig. 4 a rear view of the device.

Referring to the drawings, in which similar reference characters indicate corresponding parts throughout the several views, A, B, and C represent the three parts composing my ice-creeper, which, as clearly shown in Fig. 3, is L-shaped in cross-section, A being a straight piece to fit the front of the heel, while B and C are the pieces to fit the sides and back of the heel and curved, as shown, for this purpose.

D represents hinges connecting the ends of part A with the side pieces B and C, while the rear ends of said pieces B and C are joined by means of a latch consisting of a tongue E, pivoted to a clip F, secured to piece B, and a loop G, pivoted to clip H on piece C. Tongue E is formed with shoulders e to prevent the loop G from sliding off said tongue when the device is open. I represents spikes secured to the bottom of parts A, B, and C.

To apply the device to the heel of a shoe, the parts are expanded, as shown in Fig. 2. The tongue E is then thrown over to the position shown in Fig. 1, and the device is locked on the heel. In opening the parts I provide a teat J on the pivoted portion of tongue E to throw loop G over to insure the separation of parts B and C.

It will be understood that my invention is applicable to other uses than as ice-creepers,

as above stated, being useful in all cases where an antislapping device is desired, such as in rafting timber.

Having thus described my invention, what I claim is—

1. In an ice-creeper, pieces shaped to surround the heel of a shoe and pivotally connected to one another and having an opening between two of said pieces, a tongue pivoted to the free end of one piece and having shoulders on its edges, and a loop pivoted to the free end of the piece on the opposite side of said opening and slidably mounted on said tongue inside of said shoulders, substantially as shown and described. 6c

2. In an ice-creeper, pieces shaped to surround the heel of a shoe and pivotally connected to one another and having an opening between two of said pieces, a tongue pivoted to the free end of one piece and having shoulders on its edges, a teat on the pivoted portion of said tongue, and a loop pivoted to the free end of the piece on the opposite side of said opening and slidably mounted on said tongue inside of said shoulders, substantially as shown and described. 70

3. In an ice-creeper, a piece shaped to fit the front of a shoe-heel, pieces, hinged thereto, shaped to fit the sides and back of the heel, a tongue pivoted to one side piece having shoulders on its edges, and a loop pivoted to the other side piece and slidably mounted on said tongue inside of said shoulders, substantially as shown and described. 85

4. In an ice-creeper, a piece shaped to fit the front of a shoe-heel, pieces hinged at each end of said front piece and shaped to fit the sides and back of the heel, all of said pieces being L-shaped in cross-section and having spikes on the parts resting on the ground, a tongue pivoted on one side piece having shoulders on its edges, a teat on the pivoted portion of said tongue, a loop pivoted on the other side piece, and slidably mounted on said tongue inside of said shoulders, substantially as shown and described. 95

In testimony whereof I hereto affix my signature in the presence of two witnesses.

HENRY S. KELLEY.
